US00D990242S

(12) **United States Design Patent** (10) **Patent No.:** **US D990,242 S**
Cheng (45) **Date of Patent:** **** Jun. 27, 2023**

(54) **CONTAINER**

(71) Applicant: **ZHEJIANG HAODA SCIENCE & TECHNOLOGY CO., LTD**, Jinhua (CN)

(72) Inventor: **Haojun Cheng**, Jinhua (CN)

(73) Assignee: **ZHEJIANG HAODA SCIENCE & TECHNOLOGY CO., LTD**, Jinhua (CN)

(**) Term: **15 Years**

(21) Appl. No.: **29/785,926**

(22) Filed: **May 27, 2021**

(51) LOC (14) Cl. **07-01**

(52) U.S. Cl.

USPC **D7/511**; D7/510; D7/392.1

(57) **CLAIM**

The ornamental design for a container, as shown and described.

DESCRIPTION

FIG. 1 is a right, front, top perspective view of a container showing my new design;

FIG. 2 is a left, rear, bottom perspective view thereof;

FIG. 3 is a right side elevational view thereof;

FIG. 4 is a left side elevational view thereof;

FIG. 5 is a front plan view thereof;

FIG. 6 is a rear plan view thereof;

FIG. 7 is an enlarged top elevational view thereof;

FIG. 8 is an enlarged bottom elevational view thereof; and, FIG. 9 is another right, front, top perspective view thereof, shown with base removed for clarity of disclosure.

In the drawings, the broken lines depict portions of the container that form no part of the claimed design.

1 Claim, 9 Drawing Sheets
